The ornamental design for a clip for mounting electrical equipment on a rail, as shown and described.

DESCRIPTION

FIG. 1 is a perspective view showing the bottom, rear and left side of a clip for mounting electrical equipment on a rail according to our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.
